UNITED STATES PATENT OFFICE.

HARRY E. ASBURY, OF PHILADELPHIA, PENNSYLVANIA, ASSIGNOR TO THE ENTERPRISE MANUFACTURING COMPANY OF PENNSYLVANIA, OF PHILADELPHIA, PENNSYLVANIA, A CORPORATION OF PENNSYLVANIA.

BOTTLE-CAPPING MACHINE.

1,245,658.

Specification of Letters Patent.

Patented Nov. 6, 1917.

Application filed February 2, 1917. Serial No. 146,137.

To all whom it may concern:

Be it known that I, HARRY E. ASBURY, a citizen of the United States, residing in Philadelphia, Pennsylvania, have invented 5 certain Improvements in Bottle-Capping Machines, of which the following is a specification.

One object of my invention is to construct a comparatively cheap and effective machine 10 for capping bottles.

A further object of the invention is to design the machine so that it can be made 15 from castings which need not be machined to any great extent, and to so design the machine that it can be used in the household.

In the accompanying drawings:

Figure 1, is a front elevation, with the operating handle in section, illustrating my improved bottle capping machine;

Fig. 2, is a transverse sectional view on the line 2—2, Fig. 1;

Fig. 3, is a sectional plan view on the line 3—3, Fig. 2;

Fig. 4, is an inverted sectional view on the line 4—4, Fig. 2;

Fig. 5, is a plan view of the platform showing the guide;

Fig. 6, is a detached perspective view illustrating the two parts of the main 30 frame;

Fig. 7, is a detached perspective view illustrating the two parts of the guide frame; and

Fig. 8, is a perspective view of a crown 35 cap used in my machine.

My improved bottle capping machine is adapted for securing crown caps to bottles, such as illustrated in Figs. 2 and 8, in which 1 is the bottle having an annular recess 2. 40 3 is the cap having a flange 4, which is crimped, the flange being of such a depth that it will enter the groove 2 in the bottle when pressure is applied by the machine.

The main frame 5 of the machine is 45 adapted to be secured to a table or to a shelf, as shown at x, and is made in halves 5^a and 5^b, clamped together by transverse screws 6. On the main frame is an extension 7, which projects over the table and 50 below the table is an extension 8 in which is clamped a nut 9. Through this nut passes a clamp screw 10 which secures the frame to the table. The frame has a reduced portion 11 on which is mounted the guide frame

12. This guide frame is made in two parts, 55 as shown in Fig. 7, and the two parts are secured to the main frame by means of screws 12^a. At each end of the guide frame are sockets for vertical rods 17. The sockets 13 are formed partly in the frame and partly by hinged clamps 14; the clamps are 60 connected together by a headed rod 15 which passes through openings in the clamps and has a handled nut 16 thereon so that, on turning the nut, the clamps 14 are drawn 65 toward each other and clamp the two vertical rods 17 in position.

A cross head 18 is carried by the rods 17 and the rods are reduced in diameter and are secured to the cross head by nuts 19. 70 In the cross head is a cylinder 20 located in the center line of the machine and mounted in this cylinder is a plunger 21 having a stem 22 which extends through the upper end of the cylinder, as shown, and surrounding the stem 22 is a spring 23 which tends to force the plunger downward toward the bottle. A pin 24 limits the downward movement of the plunger. The opening for the cylinder directly below the plunger is beveled, as shown, and at the back of the cross head is a lug 25 forming a gage when setting the cross head.

Mounted in the main frame 5 is a plunger 26 carrying the table 27 on which the bottle 85 is mounted. The plunger is prevented from turning in the main frame 5 by a rib 35 on the plunger, which is adapted to a groove 36 in the frame. The plunger is made cruciform in cross section, in the present instance, 90 to lighten the machine. On the table is a V-shaped guide 28 having a stem 29 which passes through a lug on the table and is held in the adjusted position by a set screw 30, so that the guide can be adjusted to accommodate bottles of different diameters in order to bring the center of the bottle in proper alignment with the plunger 21 in the cross head 18.

31 is a hand lever having trunnions 32 100 mounted in openings 32^a in the main frame, and the short arm of this lever 31 is connected to the plunger 26 by a link 33 so that, on depressing the lever 31, the table 27 will be raised.

In order to return the table and the lever to their normal positions, I mount a coiled spring 34 within the casing formed by the

frame 5. One end of the coiled spring is attached to the trunnions 32 of the lever 31 and the other end is hooked onto a projection 34^a in the casing. Stops 37 and 37^a limit the movement of the hand lever 31.

In machines of this type it is essential that the parts can be adjusted to a bottle so as to insure the proper capping of the bottle. This is accomplished by limiting the movement of the lever so as to limit the elevation of the table and, in order to properly locate the cross head with respect to the table, the lug 25 is provided, and a bottle placed on the table without the cap is so located that the cross head can be forced down until the gage lug comes in contact with the top of the bottle, then rods carrying the cross head are clamped in position, thus setting the machine for bottles of a given height and, when the cap is applied to the mouth of the bottle and the lever forced down until it comes in contact with its stop 37, the bottle will be raised to the proper distance to allow the cap to be crimped accurately and securely onto the mouth of the bottle.

The operation is as follows:—

The cross head is adjusted vertically to the height of a bottle to be capped and the guide 28 is also adjusted to the diameter of the bottle. A cap, such as illustrated in Fig. 8, is placed on the bottle and by merely depressing the lever to its full extent, the movement being limited by the stop 37, the bottle, with the cap thereon, is forced against the plunger 21 and the beveled edge of the cylinder forces the corrugated flange of the cap into the groove 2 of the bottle, securely fastening the cap to the bottle. On releasing the lever it will be returned against the stop 37^a by the spring and the bottle with the cap will be withdrawn from the cross head and can be removed and another substituted for it.

By making the main frame 5 in two parts, as shown in Fig. 6, and the guide frame also in two parts, as shown in Fig. 7, these elements can be made of simple castings without machining or elaborate fitting, as machines of this type must be made cheaply so as to be sold at a reasonable rate to householders and to those who do a comparatively small amount of bottling.

I claim:—

1. The combination in a bottle capping machine, of a table; a cross head; means for adjusting the cross head; means for moving the table and cross head in respect to each other; and a gage lug on the cross head arranged to rest on the top of the bottle when the machine is being set so as to insure the proper adjustment of the machine to certain size bottles.

2. The combination in a bottle capping machine, of a frame; a table mounted on the

frame; an operating lever for raising the table; means for limiting the movement of the lever; a cross head; means for adjustably securing the cross head to the frame; crimping means carried by the cross head; 70 and a gage lug on the cross head so that when a bottle is mounted on the table the cross head is adjusted so that the lug will rest on the top of the bottle, insuring the proper operation of the machine when the 75 bottle is capped.

3. The combination in a bottle capping machine, of a main frame; a guide frame clamped thereto; rods mounted in the guide frame; means for adjustably holding the 80 rods in position; a cross head carried by the rods; a spring-pressed plunger mounted in the cross head, said cross head being shaped so as to cause the flange of a cap to be pressed onto a bottle when the bottle 85 is forced against the cross head; a table mounted in the main frame; and a lever for forcing the table upward so that the bottle and the cap will be clamped between the table and the plunger in the cross head. 90

4. The combination of a main frame made in two parts, each part having a clamp section arranged to extend over a table; a nut confined between the two parts of the main frame; a clamp screw adapted to the nut; 95 a two-part guide frame clamped to the main frame; vertical rods adjustably mounted in the guide frame; a table having a plunger adapted to the main frame; a lever connected to the plunger of the table; a 100 cross head carried by the upper ends of the rods; and a spring-pressed plunger in the cross head, the cross head being shaped to act upon the flange of a cap, which is mounted on a bottle carried by the table so 105 that, when the lever is moved, the table will be raised and the flange of the cap will be forced onto the bottle.

5. The combination in a bottle capping machine, of a main frame made in two parts, 110 each part having a bearing for a plunger and recessed to receive a lever and having a clamping member arranged to be secured to a table; a plunger mounted in the main frame; a table on the plunger; means for 115 preventing the plunger turning; a lever having trunnions mounted in openings in the main frame; a link connecting the lever with the plunger of the table; a guide frame having a socket at each end; a rod mounted in 120 each socket; a cross head carried by the rods, the said cross head having a cylinder formed therein; and a spring-pressed plunger mounted in the cylinder and arranged to engage the cap on the bottle so that as the 125 table is raised by the lever the cap will be forced onto the bottle and its flange will enter the groove in the bottle.

6. The combination in a bottle capping machine, of a main frame; a two-part guide 130

frame clamped to the main frame; a socket at each end of the guide frame; rods adapted to the sockets; pivoted clamps for securing the rods in the position to which they are adjusted; a bolt extending from one clamp to the other; a nut on the bolt for drawing the clamps together; a cross head carried by the upper ends of the rods, said cross head having a cylinder therein flared at its outer edge; a spring-pressed plunger located within the cylinder; a table carried by the main frame; and means for vertically moving the table so as to cause the bottle with the cap thereon to be forced against the spring-pressed plunger of the cross head.

7. The combination in a bottle capping machine, of a two-part main frame having means for clamping the frame to the table, each part being shaped to receive a plunger and recessed to accommodate the operating lever; a connecting link; a guide frame made in two parts and secured to the reduced portion of the main frame; a clamp at each end of the guide frame forming a socket; a rod mounted in each socket; means

for causing the clamps to engage the rods; a cross head carried by the upper ends of the rods, said cross head having a cylinder flared at its lower end; a spring-pressed plunger mounted in the cylinder; a table having a plunger located in the main frame; means for preventing the table from turning in the frame; an operating lever having trunnions mounted in the main frame; a link connecting the short arm of the lever with the plunger; a spring attached to one of the trunnions of the lever and to a lug on one section of the casing; a stop on the casing to limit the downward movement of the lever; and a guide on the table for the bottle so that, when the bottle is placed on the table with the cap in position and the lever is operated, the table will be raised so as to force the cap in contact with the plunger of the cross head, and, on continuing the movement until the lever comes in contact with its stop, the flange of the cap will be clamped to the bottle.

In witness whereof I affix my signature.
HARRY E. ASBURY.
